CLAIM

The ornamental design for a glove cuff, as shown and described.

DESCRIPTION

FIG. 1 is a front elevational view of an embodiment of a glove cuff.

FIG. 2 is a rear elevational view of the glove cuff of FIG. 1.

FIG. 3 is a left elevational view of the glove cuff of FIG. 1.

FIG. 4 is a right elevational view of the glove cuff of the FIG. 1; and,

FIG. 5 is a bottom plan view of the glove cuff of FIG. 1.

The top plan view is not claimed.

Features illustrated with dashed lines are not considered features of the invention being claimed, but rather illustrate an exemplary environment for the claimed features illustrated with solid lines.

The type of the material of the cuff is not claimed. Exemplary materials for the glove cuff include but are not limited to leather, synthetic leather, natural (e.g. cotton) or synthetic fabric, woven or unwoven, or combinations thereof.
